LIQUID COOLER

Richard Markley, Jr., Smyrna, Del., assignor to
 Wilson Cabinet Corporation, Smyrna, Del., a
 corporation of Delaware

Application July 31, 1936, Serial No. 93,739

11 Claims. (Cl. 62—101)

Liquid coolers are suitable and adaptable for use in many varied ways, but for the purpose of illustrating one form which the present invention may take I have in the drawing and in the hereinafter following description illustrated and made reference to a liquid cooler which is particularly adapted for the purpose of cooling milk in cans.

The agitator which comprises a very important feature of the present invention is a particularly advantageous addition to a cooler utilized for the purpose of cooling milk for the reason that it has been found necessary to cool milk as rapidly and quickly as possible, and my improved agitator when applied to a milk cooling cabinet speeds up greatly the refrigerating or cooling action of the cooler with the result that a rapid cooling of the milk can be quickly obtained.

Although in the drawing and description I have illustrated a liquid cooler cabinet in which the water or other liquid is cooled by a vertically disposed cooling coil it is to be understood that the coil could be disposed horizontally or otherwise or that the coil could be entirely dispensed with and replaced by ice or any other well known cooling or refrigerating medium.

I have found however that an electric refrigerating medium in the form of a vertically disposed coil constructed and installed in the cabinet in the manner illustrated in the drawing and hereinafter described, is particularly well adapted for obtaining rapid cooling of the liquid. Notwithstanding this fact it is to be distinctly understood that the present invention is not limited to a cabinet built in exact accord with that illustrated and described nor to a refrigerating element built and installed in the exact manner illustrated and described, but to the contrary my present improved water or liquid impeller or agitator will when applied to any liquid cooler speed up materially the cooling of the liquid, and is therefore an invention which can be advantageously used in connection with any liquid cooler.

I have found that the operation of a liquid cooler is materially speeded up by providing means to cause a circulation of the water to be cooled over, about or around the refrigerating element or medium. I have also found that to accomplish this circulation of the liquid the impeller or agitator to obtain the best results should be constructed so that in its operation eddying of the liquid is reduced to the minimum if not entirely eliminated, all of which will be explained in more detail hereinafter.

From the foregoing it will be obvious that the present invention has as an object the provision

of a liquid cooler which is highly efficient and rapid in operation. Another object will be understood as being that of providing in combination with a liquid cooler improved means for causing the circulation of the liquid in respect to the cooling or refrigerating element. Another object of the invention is the provision of an agitator or impeller of improved construction and operation.

Other specific objects, novel features of construction and improved results of the invention will appear in more detail from the following description when read in the light of the accompanying drawing.

In the drawing:

Figure 1 is a perspective view of the present invention showing its application to a liquid cooler or cabinet utilizing a vertically disposed coil as the refrigerating element, a portion of the figure being broken away and shown in section to better illustrate the invention.

Figure 2 is a fragmentary enlarged view in vertical section illustrating the movement of the liquid obtained when the agitator or impeller is in operation.

It being understood, as mentioned, that the drawing illustrates only one embodiment which the invention may take, specific description of the cooler and cabinet appearing in the drawing will now be given.

A rectangular cabinet 1 is provided with a top comprising a fixed portion 2 and a hinged portion 3. This cabinet is preferably formed with spaced walls between which are arranged insulating material, but the particular configuration and structure of the cabinet forms no part of the present invention and further detail description of it is unnecessary.

The refrigerating element, when a vertically disposed coil type is utilized, is preferably secured to the rear wall of the cabinet by a bracket 4. The cooling coil is illustrated at 5 and a refrigerant is adapted to be circulated through this coil in the well understood manner common to refrigerating coils and as the means for producing and causing the circulation of the refrigerant forms no part of the present invention and as any of the well known makes of machines now in use can be used for this purpose no illustration of it is given nor is any detail description of it considered necessary.

The coil is preferably mounted between baffles one of which is designated at 7 and is positioned at the front or outer side of the coil and is supported by a bracket 6 which is secured to the

bracket 4. The other baffle is designated at 7' and is carried by the bracket 4. Both of these baffles are preferably in actual and intimate contact with the coils and serve as fins for transmitting heat from the water, in which the coil and baffles are submerged, to the coil. The baffles 7 and 7' terminate short of the top and bottom of the coil but are completely submerged within the water to be cooled, as clearly appears 10 in Figure 2 of the drawing.

In utilizing the cabinet or cooler for cooling milk in cans the cans are placed within the cabinet and completely submerged within the water. Due to the baffle arrangement there is a natural 15 circulation of water due to the fact that the water enclosed between the baffles is quickly refrigerated and tends to settle to the bottom thus drawing warm water to the coils. This water circulation is inherent in a liquid cooler built in the manner 20 thus far described.

It has been found however, that this natural circulation of water is not sufficiently rapid to obtain the rapid cooling of the water and in turn the rapid cooling of the milk which is necessary 25 and desirable. It is for this reason that the present improved agitator or impeller is utilized in conjunction with the cooler cabinet.

Referring now to the impeller or agitator it will be seen that angle irons 8 and 9 are secured to 30 the bracket 6 and that a guard 10 is in turn secured to and supported by these angle irons.

The fixed top portion 2 of the cabinet is provided with brackets 11 carrying an electric motor 12 the shaft 13 of which is vertically disposed and 35 extends into a suitable opening 14 formed in the top and through the medium of a coupling member 15 has connection with a vertically disposed shaft extension 16 carrying at its lower end a propeller 17 preferably disposed slightly below the 40 guard 10 to prevent the propeller from being injured by milk cans as they are placed into or removed from the cabinet.

A disc 18 which for want of a better name I have termed a turbulence disc, is secured to the 45 propeller shaft 16 at a point slightly above the guard 10 and this disc is fixed to and revolves with the shaft.

It is to be noted that the propeller and its disc are quite close to the surface of the water. By 50 placing the propeller in this position it is possible to use a short propeller shaft, and due to the shortness of the shaft any tendency for the shaft to whip is eliminated notwithstanding the fact that no shaft bearing is provided.

A short propeller shaft and the elimination of a 55 shaft bearing is however only one of the advantages of placing the propeller close to the water surface or level. To bring about the rapid cooling of the water it is desirable to pull or force the 60 warm surface water downwardly and mix it with the cool water adjacent the bottom of the cabinet and also to cause circulation of the water about the refrigerating element or the refrigerating medium or coil 5. However, without provision of 65 the disc 18 it would be impossible to place the impeller as described. This disc prevents water swirl or eddying which would be inherent in connection with the use of a propeller placed close to the surface of the water. Without this disc 70 there would be swirling and eddying and large quantities of air would unquestionably be pulled or sucked down through the water and particularly around the rotating propeller shaft. This swirling or eddying would reduce materially the circulation of the water by the propeller and 75

would cause objectionable noise and would additionally cause vibration. The vibration would be extremely disadvantageous and would require a propeller shaft bearing. Furthermore the vibration would increase the wear on the working parts 5 and would of course shorten the life of the entire unit.

The provision of the turbulence disc has, I have found, overcome all of these objections and has permitted the positioning of the propeller closely 10 adjacent or only slightly below the water surface to obtain all of the advantages due to this particular positioning of the propeller. The disc permits the use of a propeller or impeller having larger blades than would be possible without the 15 provision of the disc with the result that the impeller can circulate and move a large volume of water per minute. It is of course to be understood that the size of the propeller, the pitch of the blades and the speed or revolution of the propeller 20 can all be varied and adjusted to suit the particular conditions to be met.

In actual operation of a cooler such as is here shown and described, assuming that the water level is slightly above the upper edges of the baffles and that a refrigerant is being forced through the coils, the water will start to circulate as the water between the baffles becomes quickly refrigerated and settles to the bottom and thereby drawing to the coils the warm water. When the electric 30 motor is started and the propeller is revolved at the desired and proper speed an additional circulation of the water within the cabinet is obtained and this additional circulation is such that the water is forced downwardly in all directions and 35 as the propeller is preferably located adjacent the coil baffles the water which is forced downwardly will pass under the lower edges of the baffles and up and through the coils and enter the main volume of water in a much cooler condition with 40 the result that as this operation is repeated continuously the water within the cabinet can be cooled quickly and rapidly to any desired temperature and can be maintained at that temperature so as to quickly and rapidly cool the milk 45 within the cans and maintain the milk in a cool condition throughout any period of time desired. It has actually been found that it is only necessary, once the milk has been cooled to the desired temperature, to operate the propeller at intervals. 50

In speaking of the ability of the present invention to rapidly cool milk I have reference not only to a cooler having a mechanical refrigerating element but to any cooler irrespective of the particular type of refrigerating element utilized as a means for cooling the water. The important feature is that of the circulation of water caused by the propeller and the construction of the propeller or impeller which permits it to be positioned at a point only slightly below the surface 55 of the water.

From the foregoing it will be seen that I have provided an improved means for circulating water within a liquid cooler; that I have provided a liquid cooler which is comparatively cheap and simple of construction yet highly efficient in operation and that the invention is limited only within the scope of the hereinafter appended claims; as it is to be recognized that the invention is not limited to the use of any particular 70 type of refrigerating element, to a liquid cooler of any particular configuration or construction, or that the propeller be necessarily driven by an electric motor as other driving means for the propeller can be equally well utilized. 75

Most important of all however is the provision of the turbulence disc which enables the impeller or agitator to be positioned closely adjacent the surface of the water so as to have all of the aforementioned and enumerated advantages and to guard positively against churning the water or causing water eddies which would tend to decrease to a very large degree the efficiency of the propeller in moving a large volume of water rapidly.

Attention is also directed to the fact that the impeller or agitator is constructed as a unit and therefore it need not be originally built into the cooler but as a unit can be quickly and readily applied to and used in conjunction with coolers already manufactured and in use.

I claim:

1. In a liquid cooler of the kind described, the combination with a container adapted to contain water in which cans of liquid are submerged for cooling, means disposed within said container for cooling said water, baffles arranged at opposite sides of said cooling means, said baffles terminating short of the water level in said container and terminating short of the bottom of the container, and a propeller mounted within the water of the container at a point slightly below the surface of the water and having its axis arranged at right angles to the surface of said water, means to drive said propeller, and means in the form of a disc mounted above said propeller for preventing churning and eddying of the water by the propeller.

2. In a liquid cooler of the kind described, the combination with a container adapted to contain water in which cans of liquid are submerged for cooling, of a cooling coil disposed within said container carrying a baffle, the baffle terminating short of the top and bottom of the coils and adapted to be submerged within the water and a propeller mounted within the water of the container at a point slightly below the surface of the water and having its axis arranged at right angles to the surface of the water and a turbulence disc disposed in a horizontal plane above the propeller and below the water surface.

3. A milk cooler of the kind described, comprising a cabinet adapted to contain water in which cans of milk are disposed, a cooling coil disposed in said cabinet, a baffle for said coil terminating short of the top and bottom of said coil and adapted to be submerged within the water of the cabinet, a vertically disposed propeller shaft extending through the top of said cabinet and having a propeller mounted on the lower end thereof for causing a circulation of the water within the cabinet and a turbulence disc mounted on said propeller shaft above said propeller, for the purpose described.

4. A milk cooling cabinet having a fixed and movable top and adapted to contain a cooling medium such as water, a cooling coil disposed along one wall of said cabinet and spaced therefrom, a baffle arranged against the inner face of said coil terminating short of the top and bottom of said coil to provide a space between said baffle and the inner wall of the cabinet, an electric motor mounted on the fixed top of said cabinet over an opening disposed therein, a vertically disposed propeller shaft connected to the motor shaft and adapted to be rotated thereby, a propeller fixed on the lower end of said propeller shaft and a turbulence disc fixed on said

propeller shaft above said propeller and adapted to be rotated therewith.

5. In a device of the character described, the combination with a container adapted to contain liquid in which cans of milk or the like are submerged for cooling, means disposed within said container for cooling said liquid, a propeller within said liquid positioned adjacent the surface thereof and rotatable on a vertical axis, a disc disposed slightly above said propeller and below the surface of said liquid, and said disc being of a diameter at least as great as the diameter of the propeller, for the purpose described.

6. In a device of the character described, the combination with a container adapted to contain liquid in which cans of milk or the like are submerged for cooling, means disposed within said container for cooling said liquid, a propeller within the liquid of the container and disposed slightly below the surface thereof and rotatable on a vertical axis, and means disposed between said propeller and the surface of said liquid to prevent said propeller from causing water swirl and eddying such as would be naturally inherent in connection with a propeller rotating close to the surface of the liquid.

7. In a device of the character described, a container having liquid therein, means to cool said liquid, a drive shaft vertically disposed in said liquid, means to drive said shaft, a propeller carried by said shaft and positioned slightly below the surface of the liquid in said container and through rotation on its vertical axis adapted to circulate water from the surface of the liquid towards the bottom of the container, and a disc of a diameter of at least as great as the diameter of the propeller positioned between said propeller and the surface of said liquid, for the purposes described.

8. In a device of the character described, the combination with a container adapted to contain water in which cans of liquid are submerged for cooling, means disposed within said container for cooling said water, a propeller within the water of the container, a drive shaft for said propeller, and a disc of a diameter at least as great as the diameter of the propeller disposed slight thereabove and rotatable with the propeller shaft, for the purpose described.

9. In a milk cooling cabinet adapted to contain a cooling medium such as water, a cooling coil disposed in one wall thereof and spaced therefrom, a baffle at one side of said coil terminating short of the top and bottom of said coil and short of the bottom of the cabinet and the surface of the cooling medium to provide a space between said baffle and the inner wall of said cabinet, a vertically disposed propeller shaft extending into said cooling medium and carrying a propeller disposed thereon at a point slightly below the surface of said cooling medium, means to drive said shaft, and a turbulence disc disposed in a horizontal plane above said propeller and below the surface of said cooling medium, for the purpose described.

10. In a structure such as defined in claim 9, wherein the turbulence disc is fixed to and rotatable with said propeller shaft.

11. In a construction such as defined in claim 9, wherein the turbulence disc is of a diameter at least as great as the diameter of the propeller and is fixed to and rotatable with the propeller shaft.

RICHARD MARKLEY, JR.
